[57] CLAIM

The ornamental design for a wristwatch, as shown and described.

DESCRIPTION

FIG. 1 is a top view of the watchcase portion of my new wristwatch design;

FIG. 2 is a bottom view thereof;

FIG. 3 is a left side view thereof;

FIG. 4 is a right side view thereof;

FIG. 5 is a front view thereof;

FIG. 6 is a rear view thereof;

FIG. 7 is a top, front, left perspective view thereof;

FIG. 8 is a top, front, right perspective view thereof;

FIG. 9 is a top view of the bracelet portion of my new wristwatch design;

FIG. 10 is a bottom view thereof;

FIG. 11 is a left side view thereof, the right side view being a mirror image thereof;

FIG. 12 is a top, right perspective view thereof.

FIG. 13 is a front perspective view of my new wristwatch design; and,

FIG. 14 is a rear perspective view of my new wristwatch design.
